UNITED STATES PATENT OFFICE.

BURTON NEAL, OF ST. LOUIS, AND GEORGE H. HEBEBRAND, OF KINLOCH, MISSOURI.

SELF-BALANCING MECHANISM FOR PRODUCING GYRATORY MOTION.

Application filed March 16, 1922. Serial No. 544,090.

To all whom it may concern:

Be it known that we, BURTON NEAL and GEORGE H. HEBEBRAND, citizens of the United States, residing in the city of St. Louis, and in Kinloch, in the county of St. Louis and State of Missouri, respectively, have invented new and useful Improvements in Self-Balancing Mechanism for Producing Gyratory Motion, of which the following is

10 a specification.

This invention relates to a novel driving mechanism for use in producing gyratory movement, and relates to novel mechanism for carrying out the same principle of operation broadly set forth and claimed in our co-pending application Ser. No. 530,089, filed January 13th, 1922. The use of this novel mechanism also involves a novel principle of operation whereby the general objects of the invention are attained.

20 The invention is particularly adapted for application to machines for sifting flour, wherein a gyratory motion is utilized for causing the travel of the stock over the various sieves, and in the drawing the invention is illustrated in connection with a plan-sifter type of machine.

The general object of the invention is to provide a novel driving mechanism for producing a gyratory movement of a body, such as a sifting machine, which will be self-balancing from the start to the maximum number of revolutions provided for.

30 Stated more in detail, it is a principal object of the invention to provide novel driving mechanism in which the driving part shall always occupy a fixed or centered position, while the driven part of the mechanism, including the body to which the gyratory motion is to be imparted, shall, in operation, be gradually thrown off center so that its central median line or axis shall travel in a circular path. By the use of the novel mechanism hereinafter described for attaining the above stated object, the gyratory movement is initiated and maintained with the minimum of irregular motions or vibrations, thus minimizing, or practically eliminating all strain from this cause on the building, or machine.

40 A further object of the invention is the provision of driving mechanism involving the use of a rolling weight for producing a concentric movement of the axis of the driven body relative to the axis of the driving mechanism or shaft, and the provision

of a compensating connection between the driving and driven mechanism operated by said weight, whereby to prevent relative displacement between the driving and driven mechanism.

50 A further object of the invention relates to the provision of novel means for controlling the outward throw or movement of the rolling weight in proportion to the speed of rotation of the body to be gyrated, whereby the off-center position of the axis of the latter relative to a vertical drive shaft, shall be gradually assumed, thus preventing irregular or uneven movement of the body with consequent excessive vibration.

With the general and special objects in view, the invention comprises a rolling weight which is adapted to roll outward under the action of centrifugal force, a member movably mounted on the driven shaft of the body to be gyrated and connected with a vertical drive shaft, a cable attached to said movable member and wound about a reduced portion of said weight, whereby as the driven body assumes an eccentric path of movement under the action of the weight, the said movable member will be correspondingly moved in an opposite direction under the influence of said weight, thus maintaining the same relative position between the driving part or shaft of the mechanism and its connection with the driven part, at all times.

60 The invention further comprises the employment of cables passed once around the larger diameter of the rolling weight at either end thereof and secured at opposite ends to the support for the weight, which act as guides to insure that the weight shall roll with its axis at right angles to its line of movement, thus preventing any binding of the weight which would restrict its free movement in either direction, as well as insuring the rolling and unrolling of the operating cable thereon in the space allotted for it.

70 The invention is illustrated in the accompanying drawing in which—

Figure 1 is a view of a multiple plan-sifter provided with our improved driving mechanism, the parts being shown in the relative positions they occupy with the machine in motion, and illustrating particularly the eccentric relation of the driving shaft to the driven shaft;

Figure 2 is a top plan view illustrating

the plate or support mounted on the driven shaft of the plan-sifter and having mounted thereon a rolling weight for producing gyroscopic movement, and around which is wound 5 a cord one end of which is attached to the compensating member of the driving mechanism, the weight being shown in the position it occupies with the machine at rest;

Figure 3 is a similar view showing the 10 position of the parts when the machine is in motion;

Figure 4 is a view in side elevation on an 15 enlarged scale of the rolling weight, with the compensating cable and guide cables applied thereto; and

Figure 5 is a cross-sectional view on the line 5-5 of Figure 4.

Referring now to these drawings, the numeral 1 indicates generally, a multiple plan-sifter machine of the type described and illustrated in a prior patent to Burton Neal, No. 1,368,826, dated February 15th, 1921, said machine being suspended from its four corners as usual with plan-sifter machines, 20 by means of wooden rods 2. The machine, as shown, comprises two sections of sieves indicated by dotted lines at 3, and between these sections at the center of the machine, a vertical space 4 is provided through which 25 extends a driven shaft 5. Mounted on the top and bottom of the machine centrally thereof, are castings 6 and 7, respectively, which provide bearings for opposite ends of the driven shaft 5, the upper casting preferably embodying a ball-bearing 8 for the upper end of said shaft. Fixedly secured on the top and bottom of the shaft 5 are plates 9 and 10, respectively. In Figures 2 and 3 we have shown the construction at the 30 top of the machine in connection with the plate 9 and as the construction at the bottom of the machine in the main is identical with that at the top, a description of the upper mechanism will suffice for both. 35 Such slight differences as exist at the bottom of the machine will be indicated later. The plate 9 is provided on its upper side and at opposite edges with what may be termed "guards" 11 which extend from points 40 directly in line with the driven shaft 5, when the latter is in its normal position, to the end of the plate. These guards are 45 preferably formed integral with the plate 9 and each provides a top rail 12 which is 50 parallel with and directly over a corresponding part 13 of the plate 9, which, in effect, is also a rail as the portion of the plate between the rails 13 is cut away. Between the rails 12 and 13 is a space 14 in 55 which works the roller 15. The guards 11 being connected to the opposite ends of the tracks 13, provide stops 16 and 17 to limit the movement of the roller in either direction. As shown particularly in Figures 2, 60 65 3 and 4, the roller 15 is provided at oppo-

site ends with annular flanges 18 which embrace the outer sides of the rails 12 and 13 at opposite sides of the plate and serve to prevent lateral movement of the roller. Preferably one of these flanged ends is removable to permit the insertion of the roller in the space 14. As more clearly shown by Figure 4, the roller 15 is centrally recessed to provide a portion 19 of reduced diameter and end portions 20 which form rolling contact with the rails 13. Secured at one end to the reduced portion 19 of roller 15 is a cable 21, the opposite end of which is secured to a slide bar 22. (Figures 2 and 3.) Secured in the end of the plate 9 between the stops 17 is a cross-bar 23. Secured in this cross-bar near the opposite ends thereof, are the ends of cables 24 which are passed once around the end portions 20 of the roller within the rails 12, 13, and have their opposite 80 ends secured to the plate 9 as indicated at 25.

Referring to Figure 1, the numeral 26 indicates the drive shaft which is driven through the medium of a pulley 27 and which has intermediate its length, a universal joint 28. The lower end of the drive shaft 26 is connected to the slide bar 22 previously referred to, as indicated at 27^a, in Figures 2 and 3. This slide bar 22 is adapted to be moved by the roller 15 through the pull of the cable 21, as hereinafter explained, and constitutes a compensating member for maintaining the drive shaft 26 in its normal vertical position. The slide bar 22 is slidably mounted at one end in the cross-bar 23 and at its other end beyond the connection 27^a in a bracket 28^a projecting upward from the plate 9. Beyond this bracket the slide bar 22 is provided with a reduced portion 29 which extends throughout a recessed extension 30 of the plate 9 and is surrounded by a coil spring 31 which is confined between a nut 32 on the end of the reduced portion of the slide bar and the bracket 28^a. As shown by Figure 3, the movement of the slide bar 22 outward under the influence of roller 15 and cable 21, is against the resistance of the spring 31. The manner of moving the slide bar 22 by means of the roller 15 and cable 21 will now be described.

In operation, with the drive shaft rotating, the plate 9 and the shaft 5 will be rotated and, due to centrifugal force, the roller 15 will start to move outward and the plan-sifter 1 will be caused thereby to begin its gyroscopic movement, as the initial movement of the roller will slightly move the shaft 26 off-center with reference to the driven shaft 5, this movement of the driving shaft being effected by a slight movement of the slide bar 22 to which the driving shaft is connected. The shaft 26 will practically be restored immediately to its vertical position by the movement outward of the driven shaft 5 in the opposite direction, and there-

after as the said driven shaft gradually moves to its maximum distance off-center, which movement, in practice, is approximately two inches, the outward movement 5 of the roller 15 correspondingly moves the slide bar 22 and prevents the shaft 26 from being moved in the direction of the driven shaft 5, thus maintaining the vertical position of the said driving shaft. The manner 10 in which the roller 15 co-operating with the cable 21, will operate to pull the slide bar 22 outward against the resistance of spring 31, will be understood by referring to Figure 5. Here it will be seen that the pull of the cable 15 21 is on the bottom of the reduced portion 19 of the roller, while the roller itself rests upon the portions 20 of greater diameter. Thus the force is applied at a point 33 of the roller above the point 34, which is the 20 pivot of the roller, or the point at which it rests on the rail 13. The tendency, therefore, of pull on the cable 21 is not to unwind said cable and cause the roller to move outward, but on the contrary, to continuously 25 over-balance said roller or cause it to turn on its pivot 34 and thus produce a rolling movement of the roller in the direction of pull on the cable 21. The converse of this proposition is equally true; that is to say, 30 provided tension is maintained on the cord 21, a force applied to the roller 13 tending to move it so as to unroll the cable 21 from the periphery of its reduced portion, will exert a pull in the opposite direction on the cord 35 21 and if the pull on the cable is of a yieldable character such, for example, as that exerted by a spring, and the force tending to move the roller outward is greater than the tension exerted by the spring, then the 40 outward movement of the roller will exert such a pull on the cable 21 as will cause it to compress the spring. It will now be seen, by referring to Figures 2 and 3, that as the roller 15 moves outward by centrifugal 45 force, the cable 21, which is secured at its end to the slide bar 22, will begin to pull said slide bar and to move it outward against the resistance of spring 31. This will continue until the roller has reached 50 the limit of its movement, determined by the stops 17, at which point the spring 31 will be compressed to its maximum and the slide bar 22 will have been moved the proportionate distance indicated by comparing its normal 55 position in Figure 2, with its extreme outward position illustrated in Figure 3. When the power is shut off and the speed of rotation of shaft 26 diminishes, the power of spring 31 soon becomes greater than the 60 centrifugal force acting on the roller 15, and the spring 31, through the slide bar 22, now acts to pull on the cable 21 and thus, in the manner previously described with reference to Figure 5, to roll the roller 15 inward 65 or toward the stops 16.

It may be stated that the above operation of the roller 15 can readily be demonstrated by using an ordinary spool and winding a few turns of cotton thereon at the center and pulling on the cotton or thread on the end 70 projecting from the bottom of the spool. An object heavier than a spool but having a central diameter considerably less than the ends, will prove more satisfactory however.

We have stated that the off-center movement of the driven shaft 5 is approximately two inches. It will be evident, of course, that in order to maintain the shaft 26 vertical, the slide bar 22 to which it is connected must be moved two inches in the opposite direction. Without going into the mathematics involved, we would state that in practice we use a roller whose larger diameter is six inches and whose smaller diameter (the diameter of the part 19) is 80 five and one-third inches. The circumference of the reduced portion, therefore, will be approximately two inches less than that of the larger portion. The cable 21 is given one turn, or approximately so, about the reduced portion of the roller, and the distance between the stops 16 and 17 is such that the roller is stopped when the cable has unwound the distance equal to the circumference of the reduced portion 19. As this distance is less by two inches than the distance measured by the rotation of the portions 20, it follows that when the roller 15 has reached the stop 17, the bar 22 will be moved outward a distance equal to the distance between the two circumferences, or two inches. 90

It is desirable that the outward movement of roller 15 shall be fairly gradual so that the roller will reach the stop 17 when the shaft 5 has reached the period of its maximum rotation. This movement of the roller 15 is dependent upon its weight and to regulate this, we form the roller 15 with recesses in either end and projecting outward from the bottom of each recess is a rod 35 on 95 which may be mounted weights 36, a greater or less number of weights being used as experience determines to be necessary. 100

The construction at the bottom of the plan-sifter and the operation involved, is 115 precisely the same as that above described with reference to the construction at the top of the plan-sifter, with the exception that at the bottom there is no driving shaft, the slide bar 22 being here provided on its under 120 side with a pin 37 which works in a recessed block 37 secured on the floor 39 of the building. The purpose of the pin 37 and block 38 is merely to prevent undue throw of the plan-sifter at the bottom and the pin is 125 moved by the bar 22 to keep it in alignment with the driving shaft 26 in the same manner as described with reference to the said driving shaft.

It will be understood, of course, that, as 130

shown in the drawings, the roller 15 when in its normal position, is to one side of the axis of the driven shaft, so that said roller is immediately subject to the action of centrifugal force when the driving shaft is placed in operation and the eccentric movement of the driven shaft therefore occurs but a short interval after the beginning of its rotation. The initial movement of the driving shaft, therefore, above referred to, is practically theoretical and under any circumstances negligible. As in the case of the construction of our prior application above referred to, the machine is always self-balancing from the start of the operation until the driven shaft has attained the maximum speed of rotation, the movement in the present case, however, being possibly more uniform and even than in the case of the prior construction referred to.

We claim:

1. In driving mechanism for producing gyratory movement of a suspended body, in combination with a driven shaft on which said body is pivotally mounted, a drive shaft, a differential drive connection between said drive and driven shafts, a rolling weight mounted on said driven shaft and operatively connected with said driving connection and operating by an outward movement under centrifugal force when said drive shaft is rotated to produce a lateral movement of the driven shaft with respect to the driving shaft in one direction and a corresponding movement of the driving connection in the opposite direction.

2. In combination with a suspended body having a driven shaft pivotally mounted therein, a rolling weight operatively mounted on said driven shaft and located to one side of the axis thereof, whereby when said driven shaft is rotated, said rolling weight will be moved outward under centrifugal action to change the center of rotation of said driven shaft and cause it to travel in a circular path, a driving shaft for rotating said driven shaft, a driving connection between said driving and driven shafts, and a cable, or the like, wound on said rolling weight and connected to said driving connection, whereby the latter will be movable by said rolling weight in its outward movement in one direction to an amount proportional to the movement of the driven shaft in an opposite direction.

3. In combination with a suspended body having a driven shaft pivotally mounted therein, a roller, acting as a weight, having one portion of less circumference than the remainder of the roller, and operatively mounted on the driven shaft to one side of the axis thereof, whereby when said driven shaft is rotated, said roller will be moved outward under centrifugal action to change the center of rotation of said driven shaft

and cause it to travel in a circular path, a driving shaft for rotating said driven shaft, a driving connection between said driving and driven shafts, and a cable, or the like, wound on the portion of the roller of less circumference and connected to said driving connection, whereby the latter will be movable by said roller in its outward movement in one direction to an amount proportional to the movement of the driven shaft in an opposite direction.

4. In combination with a suspended body having a driven shaft pivotally mounted therein, a roller, acting as a weight, having a reduced portion and operatively mounted on said driven shaft to one side of the axis thereof, whereby when said driven shaft is rotated, said rolling weight will be moved outward under centrifugal action to change the center of rotation of said driven shaft and cause it to travel in a circular path, a driving shaft for rotating said driven shaft, a driving connection between said driving and driven shafts and maintained in a given position under spring pressure, and a cable, or the like, wound on the reduced portion of said roller and having its outer end passed from the under side of the roller and connected to said driving connection, whereby the latter will be movable against the resistance of its spring by said roller in its outward movement in one direction to an amount proportional to the movement of the driven shaft in an opposite direction.

5. In combination with a suspended body having a driven shaft pivotally mounted therein, a rolling weight having a reduced portion and operatively mounted on said driven shaft to one side of the axis thereof, whereby when said driven shaft is rotated, said roller will be moved outward under centrifugal action to change the center of rotation of said driven shaft and cause it to travel in a circular path, a driving shaft for rotating said driven shaft, a driving connection between said driving and driven shafts and maintained in a given position under spring pressure, and a cable, or the like, wound on the reduced portion of said roller and having its outer end passed from the under side thereof and connected to said driving connection, whereby the latter will be movable against the resistance of its spring by said roller in its outward movement in one direction to an amount proportional to the movement of the driven shaft in an opposite direction, the difference in diameters between the reduced and main portions of said roller being so proportioned that when the cable has unwound therefrom through one complete revolution of the roller, the extent of off-center movement of the driven shaft occasioned by the outward movement of the roller, will correspond to the movement in the opposite direction of

the driving shaft effected by the pull of said cable.

6. In combination with a suspended body having a driven shaft pivotally mounted therein, a rolling weight having a reduced portion and operatively mounted on said driven shaft to one side of the axis thereof, whereby when said driven shaft is rotated, said roller will be moved outward under centrifugal action to change the center of rotation of said driven shaft and cause it to travel in a circular path, a driving shaft for rotating said driven shaft, a driving connection between said driving and driven shafts and maintained in a given position under spring pressure, a cable, or the like, wound on the reduced portion of said roller and having its outer end passed from the under side thereof and connected to said driving connection, whereby the latter will be movable against the resistance of its spring by said roller in its outward movement in one direction to an amount proportional to the movement of the driven shaft in an opposite direction, the difference in diameters between the reduced and main portions of said roller being so proportioned that when the cable has unwound therefrom through one complete revolution of the roller, the extent of off-center movement of the driven shaft occasioned by the outward movement of the roller, will correspond to the movement in the opposite direction of the driving shaft effected by the pull of said cable, and means for limiting the outward movement of said roller.

7. In combination with a suspended body having a driven shaft pivotally mounted therein, a roller, acting as a weight, having a centrally reduced portion and operatively mounted on said driven shaft to one side of the axis thereof, whereby when said driven shaft is rotated, said roller will be moved outward under centrifugal action to change the center of rotation of said driven shaft and cause it to travel in a circular path, a driving shaft for rotating said driven shaft, a driving connection between said driving

and driven shafts maintained in a given position under spring pressure, a cable, or the like, wound on said roller and having its free end passed from the bottom thereof and connected to said driving connection, whereby the latter will be movable by said roller in its outward movement in one direction to an amount proportional to the movement of the driven shaft in an opposite direction, and cables, or the like, wound once upon said roller on opposite sides of said reduced portion and having their ends fixedly secured with reference to said roller, whereby in the movement of said roller, said cables will be wound up from one side and unwound from the other of said roller and thereby serve to guide the same in its movement in a right line.

8. In combination with a suspended body having a driven shaft pivotally mounted therein, a plate, or the like, secured on one end of said driven shaft, a roller, acting as a weight, having a centrally reduced portion and operatively mounted on said plate to one side of the axis of said driven shaft, whereby when said driven shaft is rotated, said roller will be moved outward under centrifugal action to change the center of rotation of said driven shaft and cause it to travel in a circular path, a spring-controlled slide bar mounted on said plate, a driving shaft having one end connected to said slide bar for rotating said driven shaft, and a cable, or the like, wound on the reduced portion of said roller and having its outer end passed from the outer side thereof and connected to said slide bar, whereby the latter will be movable against the resistance of its spring by said roller in its outward movement in one direction to an amount proportional to the movement of the driven shaft in an opposite direction and thus maintain the driving shaft in a relatively fixed position.

In testimony whereof, we have hereunto set our hands.

BURTON NEAL.
GEORGE H. HEBEBRAND.
